United States Patent Office

Des. 177,708
Patented May 22, 1956

177,708

SPOON OR SIMILAR ARTICLE

Jose Barata y Barrera, Baltimore, Md., assignor to The Stieff Company, Baltimore, Md., a corporation of Maryland

Application September 26, 1955, Serial No. 38,090

Term of patent 14 years

(Cl. D54—12)

FIG. 1

Fig. 1 is a front elevational view of a spoon showing my new design;

Fig. 2 is a rear elevational view thereof; and

Fig. 3 is a side elevational view thereof.

I claim:

The ornamental design for a spoon or similar article, substantially as shown.
